WILLIAM F. MANNING, OF DETROIT, MICHIGAN.

TOOL FOR SEPARATING AND OILING SPRINGS.

1,192,922.

Specification of Letters Patent.

Patented Aug. 1, 1916.

Application filed April 2, 1915. Serial No. 18,663.

To all whom it may concern:

Be it known that I, WILLIAM F. MANNING, a subject of the Kingdom of Great Britain, residing at Detroit, in the county of Wayne, 5 State of Michigan, have invented certain new and useful Improvements in Tools for Separating and Oiling Springs; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to tools for separating and oiling leaf springs, and consists in the construction and arrangement of parts hereinafter fully set forth.

20 The object of the invention is the provision of a tool which may be employed to first force the leaves of a composite leaf-spring, and more particularly of a vehicle leaf-spring, to a spaced relation, and which 25 may then be employed to discharge a suitable lubricant between the leaves so spaced, thereby lubricating and reducing friction between the contacting surfaces of the leaves and obviating the tendency of the springs to 30 squeak when in action. This object is attained by the employment of the structure illustrated in the accompanying drawings, wherein:

35 Figure 1 is a view in side elevation of a tool embodying my invention, showing in cross section a leaf spring engaged by said tool and having two of its leaves spaced thereby. Fig. 2 is a longitudinal sectional view of the tool. Fig. 3 is a cross sectional 40 view on line 3—3 of Fig. 2. Fig. 4 is a plan view of that end portion of the tool which is provided with jaws for engaging a spring.

Referring now more particularly to the drawing, wherein like reference characters 45 designate similar parts in all the views, the numeral 1 designates the frame or body of the tool, which is preferably formed of malleable cast-iron or steel. A pair of slide 50 bearings 2 and 3 and a socket member 4, all alined, are formed integral with the frame 1, the bearing 2 and the member 4 being at opposite ends of the frame and the bearing 3 being at an intermediate point. Between the bearing 3 and member 4, the frame is 55 curved and off-set laterally to form a "goose-neck", whereby a space is formed between said parts 3 and 4, such as will allow the tool

to be engaged with a vehicle spring 5, as shown in Fig. 1.

The bearings 2 and 3 are of different construction, the latter having a tubular opening, while the former constitutes an arch, the opening of which communicates with a housing 6 formed integral at the terminal of the body 1. In said bearings there is mounted to slide longitudinally a tubular member 7, which normally projects slightly beyond the bearing 3 and considerably beyond the bearing 2. Upon the latter projecting portion there is mounted fast a grip or handle 8, retained upon the member 7 by a screw-cap 9 engaged with the terminal of said member.

Between the body of the tool and the member 7, a rack-bar 10 is rigidly secured to said member, and is extended through the bearing 2, the sides of the rack having sliding contact with the bearing, thus preventing rotation of the member 7. Preferably, the rack will have its top face longitudinally grooved, whereby it may partially embrace the member 7, as is best shown in Fig. 3. The rigid relation between the rack and said member may be secured by brazing or other suitable common expedient. Engaged with said rack is a mutilated pinion 11 arranged within the housing 6, and journaled upon a pin 12, the ends of which are rigidly mounted in the side walls of said housing. Said pinion is integrally provided with a handle for manually actuating its rotation. To permit rotation of the pinion through displacement of its handle between the two positions respectively illustrated in full lines and dashed lines, the housing 6 is made open at its rear and bottom. It is apparent that a sliding motion may be imparted to the member 7 by an angular displacement of the handle.

For engagement with the leaves of the spring 5, relatively movable jaws 14 and 15 are respectively rigidly seated within the socket member 4 and the adjacent extremity of the member 7. The jaws are formed with chisel-shaped heads having cylindrical shanks, the latter being brazed or otherwise rigidly retained within the members 4 and 7, as is best shown in Fig. 2.

It is preferred to form shoulders 16 at the junctures of the heads and shanks of the jaws, which shoulders abut against the members 4 and 7 respectively to serve as limiting stops. The head 15 is so proportioned as to offer no obstacle to withdrawal of the member 7 from its bearings.

The structure so far described forms a

complete tool so far as regards its function of separating the leaves of a vehicle spring, and this operation will be explained before further describing the construction. The operator will grasp the member 8 with one hand and with the other will manipulate the handle 13. After bringing the tool to a position in which the jaws are just below the spring, it is raised upwardly to position 10 a jaw upon each side of the spring, this being made possible by shifting the handle to substantially the position shown in dash-lines and thus spacing the jaws a distance greater than the transverse width of the 15 spring. The handle 13 is now displaced toward the position illustrated in full lines, until the jaws are brought into contact with the spring at the intersection of two of its adjacent leaves. The handle 13 is now displaced to substantially the position shown 20 in full lines, sufficient force being exerted to wedge the jaws between said adjacent leaves, separating and providing a space 17 between the same into which a lubricant may 25 be discharged.

The features of the tool which adapt it to inject oil between the spring leaves will now be described. An oil duct 18 extends longitudinally and centrally through the 30 shank of the jaw 15 and into the head thereof where it communicates with two divergent branch ducts 19 which open adjacent the intersection of the sides and point of the head. These ducts are to afford a discharge 35 of lubricant from within the tubular member 7, said member being made to serve as a lubricant reservoir. To induce and control the discharge of lubricant from this reservoir, a plunger head 20 is mounted 40 for reciprocation therein, and a rod 21 rigidly engaged with said plunger is extended slidably and centrally through the cap 9. Exterior to said reservoir, the rod 21 is terminally formed with a spherical 45 knob or handle which facilitates the manual reciprocation of the rod and plunger head. A supply of lubricant may be introduced into the reservoir through the rear end thereof by first unscrewing the cap 9 and 50 completely withdrawing the plunger head from the reservoir, or if the lubricant be an oil, the jaw 15 may be immersed in the lubricant and the plunger-head displaced rearwardly to draw in the lubricant through 55 the ducts 18 and 19.

It will be seen from the foregoing description that a tool of this construction serves both to space the component members of a leaf-spring and to discharge lubricant between said members when spaced.

It is to be noted that the parts of this

tool will preferably be so proportioned that when passed between the spokes of a vehicle wheel to lubricate the springs of the vehicle, the handle members 8 and 13 will 65 be outside of the wheel and the latter may be rocked without the wheel interfering.

The invention is presented as including all such changes and modifications as properly come within the scope of the following 70 claims.

Having thus fully set forth my invention, what I claim as new, and desire to secure by Letters Patent, is:

1. A tool comprising a frame having a 75 pair of slide-bearings, one of which is arched and the other formed with a tubular opening, an elongated member slidable in said bearings, a rack longitudinally mounted upon said member extending through the 80 arched member and engaging the same to prevent rotation of said elongated member, a pinion engaging said rack mounted upon said frame, means for rocking said pinion to actuate sliding motion of the elongated 85 member, and a pair of coöperating jaws respectively carried by the sliding member and by the frame, one of said jaws being tapered.

2. A tool comprising a frame, having a 90 slide bearing, a non-rotatable sliding member received by said bearing, a rack mounted upon the sliding member, a mutilated pinion normally engaging said rack and rotatable to a position clearing the same, means for 95 rocking said pinion to actuate the sliding member, and a pair of coöperating jaws respectively carried by said sliding member and by the frame, one of said jaws being tapered.

3. A tool for separating and oiling the 100 leaves of springs, comprising a frame, a tubular member slidably mounted upon said frame, forming a reservoir for lubricant, means for manually actuating the sliding 105 member, a pair of coöperating jaws, respectively carried by the frame and by one end of said tubular member, the other end thereof being capped, one of said jaws being tapered and having a passage communicating 110 with said tubular member, a plunger-head reciprocatory within the tubular member, and a rod rigidly connected with said plunger-head and projecting through the capped end of the tubular member.

In testimony whereof, I sign this specification in the presence of two witnesses.

WILLIAM F. MANNING.
